UNITED STATES PATENT OFFICE.

ARTHUR McDougall DUCKHAM, OF ASHSTEAD, ENGLAND.

DISCHARGING VERTICAL RETORTS.

1,211,301.

Specification of Letters Patent. Patented Jan. 2, 1917.

Application filed May 19, 1915. Serial No. 29,147.

To all whom it may concern:

Be it known that I, ARTHUR McDougall DUCKHAM, a subject of the King of Great Britain, residing in Ashstead, Surrey, England, have invented certain new and useful 5 Improvements in Discharging Vertical Retorts, of which the following is a specification.

The well-known discharging device of the 10 Woodall & Duckham vertical retort comprises a retort extension having a curved side and terminating in substantially gas-tight hopper from which the coke is withdrawn by periodically opening a curved 15 water-sealed door (*f* in the accompanying drawing), and a toothed roller mounted to rotate continuously on a horizontal axis at the foot of the curved side.

In one of my systems of carbonization in 20 vertical retorts I apply a constant mechanical pressure to the charge in the retort, so that the discharging roller has to support not only a part of the weight of the charge but also the said mechanical pressure. It 25 follows that the teeth of the roller have to move against a very considerable pressure which not only damages them but increases the consumption of power. To avoid this objection the present invention substitutes 30 for the roller as a feature of the combination an endless chain belt traveling over two rollers. In this manner there is obtained the incidental advantage that the necessary supporting surface may be accommodated 35 in a smaller space than is possible when a roller is used. An endless chain belt traveling on two rollers is not new as a device for discharging a vertical retort, and no claim is herein made for such a belt *per se*.

40 The accompanying drawing, which is a vertical section through the bottom extension of the retort *a* and the discharge hopper *b*, illustrates the invention.

The chain belt *c* extends around the continuously rotating rollers *d*, its engagement with pins on these rollers causing its upper part to move in the direction of the arrow. Being situated at the foot of the

curved side *e* of the retort extension, it supports some portion of the weight of the charge in the retort, and continuously carries forward pieces of coke from this charge until they fall over the front roller *d* into the hopper *b*, the construction of which is well known.

55 It is preferable that the chain belt should have a substantially continuous surface so that its links are best constructed to fit into each other in the manner usual in the construction of underfeed stoking apparatus 60 and the like. This feature and also the mode of engagement of the belt with pins on the rollers being well-known to engineers, are not here further described.

The present invention is shown and described, but not claimed, in my co-pending application Serial No. 29,145.

Having thus described my invention and the best means I know of carrying the same into practical effect, I claim:

70 Apparatus for discharging vertical retorts in which a positive mechanical pressure is imposed upon the charge therein, comprising, in combination, a substantially-vertical extension on the retort disposed directly below the open bottom thereof and embodying a curved side wall which extends inwardly and downwardly from one side wall of said bottom to a point substantially in line with the opposite side wall, so as to sustain a 75 portion of the weight of the charge; an endless chain belt disposed at the foot of said wall and having one end overhung by the same, so as to sustain the remainder of the weight of the charge; and means for driving said belt in a direction to enable it to discharge continuously at its opposite end the charge which it supports.

75 In testimony whereof I have signed my name to this application in the presence of 80 two subscribing witnesses.

ARTHUR McDougall DUCKHAM.
